UNITED STATES PATENT OFFICE.

THOMAS H. SEELY, OF MALDEN, MASSACHUSETTS, ASSIGNOR TO UNITED SHOE MACHINERY CORPORATION, OF PATERSON, NEW JERSEY, A CORPORATION OF NEW JERSEY.

LASTING MACHINE.

Application filed May 26, 1923. Serial No. 641,685.

The present invention is herein shown and described with particular reference to its application to machines for lasting boots and shoes, although in various of its aspects 5 the invention is not limited to such use. In the drawings the invention is illustrated as embodied in a lasting machine which operates on different portions of the upper materials successively, after the manner of the 10 well-known hand method lasting machine. An example of this type of machine is disclosed in Letters Patent of the United States No. 584,744, granted June 15, 1897, on application of Ladd & McFeely.

15 In Letters Patent of the United States No. 1,477,011, granted December 11, 1918, on my application, is disclosed mechanism, operated by power of the machine under control of the operator, for effecting the 20 shifting of the work positioning means, changing the kind of tack to be inserted, and varying the degree of its insertion. An object of this invention is still further to facilitate effecting such adjustments without 25 sacrifice of any of the advantages of said prior mechanism.

In my application for Letters Patent of the United States Serial No. 398,056, filed July 22, 1920, is disclosed, among other improvements, mechanism having a similar object in view, and the present invention, in so far as its subject-matter is common to said application, is a continuation thereof.

Further objects of this invention are generally to improve and perfect machines of this type without sacrificing the advantages of prior constructions and to provide a machine which will be more rapid, durable, convenient and effective than prior machines 40 for this purpose.

In accordance with features of the invention the illustrated machine comprises simplified mechanism for effecting the plaiting movements of the gripper, said mechanism 45 comprising a rocking sleeve or shaft, having mounted thereon a member which can swing on an axis transverse to that of the sleeve with connections from said member to the gripper for effecting its lateral and 50 twisting movements; novel connecting

means from said member to the gripper which avoids excessive linkage and consequent lost motion while providing for lateral adjustment of the gripper; improved mechanism for effecting by power of the 55 machine the shifting of the lasting instrumentalities from a condition of adjustment for operation on one portion of a shoe to a condition of adjustment for operating on another portion of the shoe; and improved 60 mechanism for controlling manually the power shifting including a knee lever, together with a construction and arrangement whereby vertical adjustment of the machine head may be effected without disturbing the 65 operative connection and adjustment of the controlling mechanism.

These and other features of the invention, including various other novel combinations and arrangements of parts, will appear more 70 fully from the following description when read in connection with the accompanying drawings and will be pointed out in the appended claims.

Certain other novel features of the invention herein shown and described, including the construction of the driver bar and the mechanism for varying its stroke, are not claimed herein but form the subject-matter of a divisional application Serial No. 171,- 80 388 filed February 28, 1927.

In the drawings,—

Fig. 1 is a side elevation, partly in section, of a hand method machine embodying the present invention;

Fig. 1^a is a sectional detail of parts shown in Figs. 1 and 2;

Fig. 2 is a perspective view of portions of the mechanism of the machine head, the supporting frame being omitted for the sake of 90 clearness;

Fig. 3 is a plan view of mechanism shown in Fig. 2;

Fig. 4 is a detail side view illustrating an adjustment for the driver bar carrier;

Fig. 5 is a front view of the gripper and operating mechanism connected therewith;

Fig. 6 is a detail side view, partly in section, of the mechanism for imparting plaiting movements to the gripper;

Fig. 7 is a detail of the gripper closing lever and its operating cam;

Fig. 8 is a view similar to Fig. 3 showing a modified construction suitable for McKay work;

Fig. 9 is a detail in side elevation of parts shown in Fig. 8;

Fig. 10 is a detail, partly in section, of the driver bar and its operating cam;

Fig. 11 is a plan view of the knee lever mechanism shown in Fig. 1; and

Fig. 12 is a detail in front elevation, partly in section, of the stop mechanism with which the machine is provided.

Referring to Fig. 1 of the drawings, the numeral 2 indicates a column upon which is mounted for vertical adjustment a head frame 5 in which is journaled a shaft 6 carrying a driving pulley 7, the shaft 6 having thereon various cams from which the operating movements of the machine are derived. A gripper 10 is given the usual closing, updraw and overdraw movements by mechanism similar to that shown in the prior patent before referred to.

The shoe is positioned laterally by one or the other of two edge gages 11, 12 and is positioned vertically by a bottom rest 13. A reciprocating wiper 14 is provided to wipe the tensioned upper into lasted position upon the shoe bottom and a tack is fed in each cycle of the machine from one or the other of two raceways 16, 17, to a pocket in the wiper 14 by which it is carried into position to be driven by a driver 18. The wiper 14 is mounted on a horizontally reciprocating slide 20, directly actuated by a cam on the shaft 6 by the following construction.

An irregularly shaped bracket member 22 (Figs. 1, 2 and 3) is secured to the slide 20 by cap screws 24, 26 which pass through slots in the bracket 22 and are threaded into the slide 20. The bracket is preferably provided with a rib 28 engaging a groove in the slide to hold the slide and bracket in correct relative position vertically. By loosening the cap screws 24, 26 the bracket may be adjusted horizontally relatively to the slide, and, for the purpose of effecting such adjustment conveniently and accurately, a screw 30 having a capstan head 31 is threaded into the bracket 22 with its head engaging a notch 32 formed in the slide 20. The screw 30 is held in adjusted position by a set screw 33. An arm 34 of the bracket carries a tapered cam roll 36 which engages a suitable cam path 37 formed in the edge of a cam on the shaft 6. The cam path 37 is designed to effect to and fro movements of the slide 20 and wiper 14 from a rearward position in which a tack is fed from one of the raceways 16, 17, to a tack pocket in the wiper, to a forward position to wipe the upper over the shoe bottom. The cam 37 acts directly, through the bracket 22, upon the slide with-

out the intervention of a lever as in prior constructions, and by the adjustment above described the rearward position of the wiper may be accurately adjusted to secure proper alignment between the tack pocket and the tack passage of the separator block 38. To counteract side thrust of the slide 20 due to the taper of the roll 36, sliding contact is provided between the slide 20 and a plate 39 held by cap screws 41 to a block 43 secured at 45 to a bracket 47 of the head frame 5. The holes in the plate 39, through which the screws 41 extend, are sufficiently elongated laterally of the slide 20 to allow the plate to be pressed against the slide before the screws are set up, so that the plate will support the slide 20 as it moves back and forth in contact therewith.

The driver 18 is connected to a driver bar 40 arranged to slide in a driver bar carrier 42. The carrier is journaled for swinging movement on trunnions 44 one of which is shown in Fig. 2, the journals being formed in a bracket 46 secured at 47 to the frame 5 of the machine head. This construction provides a long and rigid bearing for the driver bar carrier so that it will withstand, during long use, the continual battering of the driver blows. The slide 20 is provided with a capstan headed screw 48 which, as the slide moves forward, engages the driver bar carrier 42 and swings it on its trunnions 44, the screw being adjusted so that when the slide has reached its forward position over the shoe bottom the driver 18 is at the proper position and angle to align with the tack pocket in the wiper 14 and when released will drive the tack through the pocket into the shoe. The rearward position of the driver bar carrier 42 is also made adjustable as shown in Figs. 2 and 4. A rod 51 passes loosely through an ear 53 on the carrier 42 and is threaded into the bracket 46 where it is maintained in adjusted position by a set screw 55. On the rod 51 is a fixed collar 57 against which the ear 53 is held by a spring 59 on the rod between the ear 53 and nuts 61 on the forward end of the rod which is slotted to receive a screw driver. By loosening the set screw 55 and turning the rod 51 the rearward position of the carrier about its pivot 44 may be adjusted and its position with respect to a separator block 38 determined. The driver bar is raised by a cam 49 on the shaft 6 (Fig. 1) and is impelled downwardly by a torsion bar 50 acting on an arm 52 between which and the driver bar is a connecting strut 54. It will be noted in Figs. 1 and 10 that the cam 49 engages a projection 56 on the driver bar 40 upon which it operates to raise the bar against the driver spring 50, and that the driver bar is provided with a like projection 56 on its front side. It is hence possible, when one of the projections 56 has become worn, to

90

130

reverse the position of the driver bar in its carrier so as to present the other projection 56 in operative relation to the cam.

In order that the tacks may at times be left upstanding from the work, as in lasting the sides of welt shoes, so that they may be conveniently pulled out, and at times completely driven as in McKay work and in the heel-seat lasting of welt work, novel mechanism is provided for arresting the stroke of the driver. In prior constructions for this purpose driver stops were arranged to close beneath a stop collar on the driver bar. It is necessary to provide buffer washers on the under side of the stop collar and it is difficult to prevent these from dropping down and getting in the way of the closing of the stops. The present construction avoids this and other objections to the old construction, including development of looseness and lost motion, and provides a very rigid and durable mechanism for arresting the driver. The upper portion of the driver bar 40 (Fig. 2) is formed as a cylindrical reduced portion 60 which carries a stop collar 61 held by nuts 62 on the portion 60. Between the collar 61 and the top of the carrier 42 is interposed a pair of wedges 63, 64. The upper wedge 63 is loosely mounted for vertical movement on the reduction 60, and the lower wedge 64 is arranged to slide transversely of the machine beneath the upper wedge 63. On the rear side the wedge 64 is guided for such movement and is held from vertical movement by a rib 65 engaging a groove in the carrier 42, and at the front side the wedge has a rib 66 engaging a groove in a cap plate 67 secured to the carrier 42 by screws 68. The wedge 64 is slotted at 70 to receive the driver bar reduction and to receive a depending portion 71 of the wedge 63 by which the wedges are held in proper alignment and which rests on the carrier 42 to transmit the blow of the driver directly to the carrier when the wedge 64 is withdrawn. The wedge 64, when moved in its guide, raises or lowers the wedge 63 to vary the space between the stop collar 61 and buffer washers 73 on the top of the wedge 63 and hence to vary the stroke of the driver. To move the wedge 64, a ball-ended link 74 is suitably connected at one end to a projection 75 on the wedge 64 and at the other end to an arm 76 secured to a rock-shaft 78, the operating mechanism for which will be hereinafter fully described.

The link 74 and the arm 76 constitute a toggle which is substantially straight when the wedge 64 is in operative position, so that any tendency of the wedge 64 to slip out from under the wedge 63, due to the blow of the driver, will be transmitted through the straight toggle 74, 76 to the shaft 78,

the wedge being thus locked in operative 65 position. When the wedge 64 is out, as shown in Fig. 2, the driver blow is transmitted directly to the carrier 42 through the rib 71 which then rests upon it. To prevent cramping of the wedge 63 against 70 the portion 60 of the driver bar when the wedge 64 is pushed under the wedge 63, an abutment 79 is provided on the carrier 42 against a vertical face of which an end of the wedge 63 bears and which takes the 75 end thrust of the wedge 63 as the wedge 64 is moved under it.

Novel mechanism, shown in Figs. 1, 5 and 6, is provided in the present machine for giving the gripper 10 its lateral and turning movements. The upper end of the shank 80 of the lower gripper jaw is hung by a ball joint 81 to the forward end of an updraw lever 82 shaped as shown in Fig. 1 and pivoted at 84 to the machine frame, 85. The rear end of the lever is operated by a cam 85 and spring 86 in the usual manner to impart yielding updraw movement to the gripper. The ball 81 is formed with teeth which engage corresponding teeth in 90 a plate 87 (Fig. 5) mounted to slide in the updraw lever transversely of the machine. An end of a link 88 is adjustably connected at 90 to the plate 87 and the other end of the link has a ball joint connection with the upper end of a lever 92 fulcrumed at 94 on the machine frame. The lower end of the lever 92 is pivoted by a pin 96 to a cylindrical slide 98 which is mounted for vertical sliding movement in an enlargement 100 of a connecting rod 102, the enlargement being slotted at 101 to permit relative vertical movement of the connecting rod 102 and the pin 96 as the direction and position of the rod 102 changes in the operation of the mechanism. The pivot pin 96 is held in the slide 98 by a set screw 104 threaded longitudinally of the slide 98 to engage the pin 96. The slide 98 is free to turn and the pin 96 is elongated and is loose in its hole in the lever 92 so that the necessary movements of the rod 102 relatively to the lever 92 during overdraw movement of the gripper can occur without causing the pin 96 to bind, the pin moving longitudinally in its hole in the lever. As will be understood, the overdraw movements are imparted to the gripper by a yoke 110 on an overdraw slide rod 112 (Fig. 1) mounted for horizontal movement and operated rearwardly by the action of a face cam 114 on a cam block 115 which acts on a roll 116. The slide rod is yieldingly actuated in a forward direction to impart overdraw movement to the gripper by a spring actuated arm 118 which engages the rear end of the rod 112. A carrier 120 (Fig. 5) has hollow cylindrical portions 125

121, 122 which are held by bearing caps 123, 123 for transverse movement in the yoke 110. The left-hand end of the connecting rod 102 passes into the hollow portion 121 and has a ball and socket connection at 124 with the lower arm or stem 125 of a T-lever 126 pivoted at 127 to the carrier 120 through which the shank of the gripper passes loosely and by movement of which the lateral and overdraw movements are imparted to the gripper. The lateral arms 128, 128, or cross bar, of the T-lever 125 are each engaged by a screw 130 threaded through a bar lever 132 which rests at its ends upon stop pins 134, 134 on the carrier 120. The bar 132 is pressed upon at its upper central portion by a plunger 136 mounted in a sleeve 140 and yieldingly depressed by a spring 142 the tension of which may be adjusted by turning the sleeve 140 which is threaded into the upper portion of the carrier 120. It will be understood that a push or pull of the rod 102 will act through the mechanism described to move the carrier 120, and hence the gripper, laterally, and that if resistance to lateral movement is offered to the gripper the T-lever 126 will be tipped on its pivot 127 and, by upward pressure on one or the other of the screws 130, will lift one end or the other of the bar lever 132 against the tension of the spring 142. In this manner movement of the rod 102 will impart to the gripper, through the spring 142, yielding lateral movement in either direction. The screws 130 may be adjusted to centralize the gripper 10 with respect to the driver 18 independently of the rod 102.

When lateral and turning movements of the gripper are desired, they may be effected by imparting longitudinal movements to the rod 102 by the following mechanism: The outer end of the rod 102 has a ball 146 seated in an arm or member 148 and held in place by a ball cap 150 secured by screws 152 (Fig. 6). The member 148 has ears 154 through which are threaded cone-ended bearing studs 156, 156, the conical ends of which are seated in sockets in a hollow rocking sleeve 158 having a bearing 157 in the machine frame (Fig. 6). Rocking movements are given to the sleeve 158 in each cycle of the machine by means of a cam operated lever 159 having a toothed segment engaging a pinion 160 on the sleeve 158. The lever 159 is pivoted at 161 to the frame (Fig. 5) and carries a roll 163 which engages a cam path 165 in the front face of the cam block 115 on the shaft 6. In Figs. 5 and 6 the parts are shown in neutral position with the ball 146 of the rod 102 in alinement with the axis of the sleeve 158 so that rocking of the sleeve will cause no movement of the rod 102. The space between the ball 146 and the pivot studs 156 of the member 148 is such that the

member constitutes an arm which, if turned upwardly or downwardly on its pivots 156, will act as a crank to move the rod 102 longitudinally when the sleeve 158 is rocked. To move and control the position of the member 148, a push rod 162 is mounted for longitudinal movement in the sleeve 158 through which it extends at both ends. At its front end it has a downwardly extending portion 164 ending in a hook which engages a pin 166 mounted in a downward extension of the member 148. Forward movement of the rod 162 will turn the member 148 so as to position the ball 146 above the center of oscillation of the sleeve 158 and cause lateral and turning movements to be imparted to the gripper in one direction, and movement of the rod 162 rearwardly will turn the member 148 to locate the ball 146 below the center of oscillation of the sleeve 158 and cause the lateral and turning movements to occur in the opposite direction.

Movement of the rod 162 is effected by rocking movement of a vertical shaft 170 having on its upper end an arm 172 in the outer end of which is clamped a pin 174. On the pin is pivoted a block 176 which engages a slot 178 in the rod 162, the slot having an arcuate bottom to permit rocking of the rod 162 with the rocking sleeve 158. The shaft 170 is associated with the mechanism for operating the edge gages and other parts now to be described.

The thin edge gage 11 and the thick edge gage 12 are arranged, as shown in Figs. 1, 2 and 3, for use alternatively each to the exclusion of the other as is usual in machines of this type. The thin gage 11 is mounted to slide horizontally on a part 180 secured to the machine head at 181. As shown in Fig. 3, a link 182 is adjustably held by a bolt and slot connection 184 to the sliding gage 11 and is pivoted at its rear end to a lever 186 having a fixed fulcrum 188 between its ends. The lever 186 has its other end connected by a link 190 to a pin 192 mounted on an irregularly shaped rocking member 194 to be further described. The pin 192 has a long bearing in one end of a link 196 which, at its other end, has fixed therein an upwardly projecting pin 198 which projects through a hole in an ear 200 of a member 202 arranged for oblique sliding movement on the part 180 toward and from the front end of the thin gage 11 from the position of Fig. 1 to that of Fig. 2. The member 202 slides on ribs 204 formed on each side of the part 180 and carries at its front end the thick gage member 12. Movement of the thick gage 12 toward and from its operative position is effected by movement of the rocking member 194 with the rock-shaft 78 to which it is fastened by a screw 195. As the pin 192 moves about 78 as a center, it acts through the link 196 to slide the thick gage 130

12 upwardly and forwardly, the link 196 having an upward movement upon the pin 198. As the slide 202 moves forwardly, the slight rotation of the pin 198 during its movement prevents the pin from binding in the ear 200 as it moves vertically on the pin. By the mechanism just described, swinging of the pin 192 with the rocking member counter-clockwise by means to be described 5 causes the thick gage 12 to be moved upwardly and forwardly into operative position, and the thin gage 11, through the link 190, lever 186, and link 182, to be moved rearwardly out of operative position. 10 Swinging of the rocking member 194 in a clockwise direction, of course, reverses the motion, causing the thick gage 12 to be withdrawn and the thin gage 11 to be moved forward into operative position. The operative 15 position of the thick gage, however, is farther back of the point where the tacks are driven than is the operative position of the thin edge gage, so that when the thick gage is used the tacks will be located at a greater 20 distance from the shoe edge, as is desirable at the heel-seat. It will be observed also that through the connections described the shaft 78 will be rocked to cause the wedge 64 to be moved out from under the wedge 63 25 when the thick gage is brought into operative position, so that the tacks will be completely driven when the thick gage is in use as it is when lasting an end portion of the shoe. When lasting the sides of a shoe with 30 the thin gage 11 in operative position, the wedge 64 will be inserted under the wedge 63 to cause the tacks to be only partially driven, as is desirable in lasting the side of a welt 35 shoe. 40 In lasting the sides of a shoe, tacks of a different kind from the kind used in lasting the end of the shoe are required, the side lasting tacks being frequently much longer and having small heads and blunter points 45 than those used for end lasting. The raceway 16 (Fig. 3) is adapted to receive long side lasting tacks and the raceway 17 tacks of a different kind for use at the end of the shoe, for example, at the heel-seat. The machine provides for the automatic shifting of 50 the raceways in conjunction with the shifting of the edge gages and the driver stop wedges. For this purpose a link 208 has a ball and socket connection at 210 with the raceway, the link 208 is threaded into a link member 212 and is provided with a set nut 214. To provide an adjustable yielding operative connection between the outer end of 55 the link member 212 and the operating member 194, a block 216 (Fig. 1^a) is adjustably secured in a recess in the member 194 by a cap screw 218 which passes through a slot in the member 194. Part of the block 216 underlies the member 212 and in the block 60 65 216 is mounted a spring plunger 219 (Fig. 5) having a conical end which engages a similarly shaped recess in the end of the link member 212 to form a pivot for the link and an operative connection between the link and the member 194. In case movement of 70 the raceway should be obstructed, for example, by clogging of tacks between the raceway and separator, power movement of the member 194 may still take place without danger of breakage or straining of parts, 75 the spring plunger 219 in that case merely passing partially or wholly out of the recess in the link 212. From Fig. 3 it will be seen that the plunger 219 is sufficiently eccentric to the fulcrum 78 of the member 194 to give 80 the required movement of the raceway and that when the parts are in the position there shown the fulcrum 78, the plunger 219 and the ball joint 210 are substantially in a straight line, and also that the face of the 85 member 194 along which the block 216 is adjustable is substantially perpendicular to this line. The block 216 can, therefore, be adjusted without materially varying the position of the raceway when the parts are 90 in the position shown; such adjustment of the block, however, will vary the movement imparted to the raceway when the member 194 is moved and provides convenient and accurate means for alining with the separator the channel 17 of the raceway which is in operative relation to the separator when the lever is moved from the position of Fig. 3 to its other position. The tack channel 16 may be alined with the separator while 95 the parts are in the position of Fig. 3 by loosening the set nut 214 and turning the ball-ended portion of the link 212. 100 It will now be clear that control of the plaiting movements of the gripper may be 105 effected by rocking the shaft 170 and that the movement of the wedges 63, 64 to control the stroke of the driver, the shifting of the raceways 16, 17 to control the size of tacks, and the alternative positioning of the edge 110 gages 11, 12 for mutually exclusive use at the ends and sides of the shoe respectively to position the shoe for the reception of tacks at different distances from the shoe edge, may all be effected by movement of the member 115 194 with its pivot shaft 78. Movement of the member 194 is effected by power of the machine under control of the operator by mechanism now to be described, including a knee lever by which also the 120 rocking of the shaft 170 to control the plaiting movements of the gripper is effected. A push bar 220 is slotted at 222 to receive a pin 224 on which is a roll 226 fitting the slot 222. The pin 224 is supported in upper and lower branches of a lever 228, both branches of which are splined on the shaft 170. The lever 228 is supported by a bracket 232 secured to lugs 234 on the column 2 by bolts 125 236. The bracket 232 carries a stop-screw 130

238 to limit outward movement of the lever 228 and a stop-screw 240 is threaded into the lever 228 in position to engage the column 2 to limit its movement in the opposite direction. To yieldingly hold the lever 228 in central or neutral position and to indicate to the operator when it is in that position, a spring plunger 242, the lower end of which is conical, is arranged in the lever 228 to engage a suitable depression formed in the upper end of a flanged pin 244 mounted in the bracket 232 and held by a set-screw 246. The flange of the pin 244 engages a guiding groove 248 in the lower branch of the lever 228. The bar 220 is pivoted by a pin 250 to a rocking member 252 and is guided between projections 254, 254 on the upper and lower branches of the lever 228. At its outer end the bar 220 has adjustably secured thereto at 256 the usual knee pad 258. When the knee pad is swung from side to side, the bar 220 will turn on its pin 250 and, through the pin and slot connection 222, 224, will swing the lever 228 and hence rock the shaft 170 to which it is splined, thus controlling the plaiting movements of the gripper through the mechanism already described.

The rocking member 252 is mounted to turn loosely on the shaft 170 having bearings thereon which are respectively above and between the branches of the lever 228. The member 252 has an upward extension 260 formed to engage a vertical slot 262 in a sleeve or tubular shaft 264 surrounding the rock-shaft 170. An inward thrust on the knee pad 258 will move the bar 220 longitudinally and rock the member 252 and hence the sleeve 264. To hold the bar 220 in its forward position a spring plunger 266 (Fig. 11) is mounted in an enlargement 268 of the member 252 in position to engage the column, and rocking movement of the member 252 is adjustably limited by stop-screws 270, 272 arranged in the member 252 on opposite sides of its axis of movement and in position alternatively to engage the column 2.

On the upper end of the sleeve 264 is clamped at 274 a U-shaped member 276 which extends around a bearing bracket 278 for the shaft 170 and is loosely mounted on the shaft 170 above the bracket. On the upper face of the U-shaped member 276 is mounted a pawl 280 in position to engage the teeth of a six-toothed ratchet wheel 282 loosely mounted on the shaft 170. Above the ratchet 282 and fixed thereto or integral therewith, is a three-projection cam 284. Above the cam, a block 286 (Fig. 3) is loosely mounted on the shaft 170, the block being embraced by a slot 288 in an operating slide bar 290 on the lower face of which are mounted two rolls 292, 294 which are so spaced that when one engages a projection of the three-projection cam 284 the

other will engage a portion of the cam between the other two projections. Rotary movement of the cam 284 will therefore impart a reciprocating motion to the operating slide 290, for, as one projection 296 (Fig. 3) leaves the roll 294, another projection 297 will engage the roll 292 and move the slide 290 forward until the cam has made one sixth of a rotation. Upon movement of the cam another one sixth of a rotation in the same direction, the motion will be reversed. The forward end of the slide 290 is pivoted at 298 to the rocking member 194 at a sufficient distance from its axis of rotation 78 to impart to the member 194 the movement required to effect the shifting of the driver stop wedge, the raceways and the edge gages, as already described. It will be observed that the ends of the projections on the cam 284 and a portion of the surface between the projections is concentric with the axis 170 of the cam, so that a slight movement of the cam when in the position of Fig. 3, for instance, will impart no motion to the slide 290.

In order to actuate the ratchet 282 and the cam 284 by power of the machine, a pawl 300 is mounted by a pin 302 on an arm 304 formed on the bracket 22 secured to the wiper slide 20. The pawl 300 has a wear plate 305 on its forward end which normally slides back and forth, as the slide 20 reciprocates, in close relation to a parallel surface formed between two adjacent teeth of the ratchet 282, no movement being imparted to the ratchet. The rear end 306 of the pawl 300 carries a wear plate 307 adjacent to which is a spring plunger 308 mounted in a boss 310 on the bracket 47 forming part of the frame 5 of the machine head. The plunger 308 has a stem 309 extending through the boss 310 and provided with adjusting nuts 311 which limit its inward movement in response to its spring 313. The nuts 311 are so set that normally the plunger 308 does not bear on the wear plate 307 and does not press the pawl 300 against a flat between the ratchet teeth. The slide 20 is therefore relieved of any friction due to the pawl 300 or plunger 308 during reciprocation of the slide in the normal operation of the machine. A pawl 314 is pivoted at 316 to ears formed on the machine frame, and at its outer end has two teeth 318, 320, the tooth 318 normally engaging a tooth of the ratchet to prevent backward movement thereof. A spring 322 is connected between a pin on the pawl 314 and a pin on the pawl 280 and serves to hold both pawls in engagement with the ratchet 282.

When the operator desires to have the driver stop, raceways and edge gages shifted from the positions which they occupy for one kind of work to the positions required for another kind of work; he pushes rearwardly

upon the knee pad 258 and thereby, through the mechanism described, rotates the sleeve 264 slightly, causing the pawl 280 to rotate the ratchet 282 far enough to cause the tooth 320 of the pawl 314 to engage the tooth of the ratchet which previously was engaged by the tooth 318. This rotation of the ratchet is sufficient to cause the pawl 300, on the next rearward movement, to engage a tooth of the ratchet which it previously was unable to reach, and upon its next forward movement to turn the ratchet one sixth of a rotation and locate another tooth of the ratchet in position to be engaged by the tooth 318 of the pawl 314. This movement of the ratchet causes the cam 284 to operate the slide 290 and effect the desired changes, as previously described. The next inward movement of the bar 220 by the operator will, of course, restore the parts to their original position, the changes being initiated at the will of the operator and completed by power of the machine.

It will be noted that as the pawl 300 moves forward with the slide 20, the spring plunger 308, being relatively stationary, will bear nearer and nearer the rear end of the wear plate 307 and hence will have increased leverage to hold the pawl 300 against the ratchet 282. This action prevents the sudden movement of the pawl 300 by the slide 20 from effecting an overthrow of the ratchet which, if sufficient, would cause the slide on its next forward reciprocation to shift the parts back to their original positions. Since, as arranged, the plunger 308 does not offer any frictional resistance to the normal operation of the slide, its spring 313 may be quite strong. If the operator pushes on the knee lever to initiate a shift while the slide is in its rearward position, as he is most likely to do with the machine momentarily stopped, he has to overcome the pressure of the plunger spring 313 to move one of the ratchet teeth by the pawl 300. At this time, however, the spring has its least advantage in its action on the pawl so that the shift is easy. The shift can be initiated in any position of the pawl, however, without objectionable effort.

The closing movement of the gripper is effected by movement of a rock-shaft 330 (Figs. 5 and 7) which is mounted in a bearing 332 formed on the side of the updraw lever 82 and in a bearing 334 formed in one end of the updraw lever pivot 84. An arm 336 of the rock-shaft 330 carries a spring plunger 338 which bears on the upper end of a gripper closing rod 340. Another arm 342 of the rock-shaft 330 is bifurcated to embrace the bearing 334 of the rock-shaft and carries a roll 346 which is acted upon by the edge face of the cam block 115 which constitutes the gripper closing cam. By this construction the rock-shaft 330 partakes of

the tipping movement of the updraw lever 82 and, in consequence, the end of the arm 342 by which the roll 346 is carried has a movement transverse to the face of the cam which, of course, has a fixed axis on the shaft 70 6. When the roll 346 is mounted in the usual manner on the arm 342, it frictionally resists movement transversely of the cam as the updraw lever is tipped and not only retards movement of the updraw lever but also 75 causes undue friction and wear of the roll and cam and of the rock-shaft bearings. To overcome these objections to the prior construction, the following construction is provided: A pin 348 on which the roll 346 is mounted is secured in the arm 342 and the portion of it on which the roll turns is longer than the width of the roll, so that as the updraw lever tips, the pin 348 can move through the roll while the roll remains in 80 the same relation to the cam 115, that is, without relative movement of the roll and cam in the direction of their line of contact. To maintain the roll 346 constantly in proper relation to the cam, cooperating rib 90 and groove formations are provided on the roll and cam. As shown, a rib 350 is formed on the roll 346 which engages a groove 352 formed in the peripheral face of the cam 115. 95

As shown in Fig. 1, the machine is provided with the usual counter-shaft 354 which is continuously driven from a source of power and has fixed thereto a friction disk 356. A cooperating disk 358 is forced 100 toward the disk 356 by a wedge 360 raised by a treadle lever 362. A pulley 364 fixed to the disk 358 is belted to the pulley 7. The machine is preferably provided, as shown in Figs. 1 and 12, with stop mechanism similar to that disclosed in Letters Patent of the United States No. 1,356,406, granted October 19, 1920, on my application. This mechanism comprises a brake shoe 366 lined with a piece of leather 368 which is 110 formed at one end as a hook to engage one end of the shoe 366 and is forced against the inner face of the rim of the pulley 7 to arrest movement of the shaft 6 at a predetermined point in the cycle, preferably 115 when the gripper is open. The shoe 366 is pivoted to a lever 370 which is acted upon to operate the shoe by a spring detent 372 mounted on a member 374 which is arranged to swing on an eccentric 376 on the shaft 6. 120 A roll 378 on the member 374 engages a beveled end on a vertically movable trip rod 380. At the proper time in the cycle, provided the trip rod is in its normal depressed position, the eccentric 376 moves the member 374 radially while the roll 378 is in contact with the beveled end of the trip rod 380, forcing the detent 372 against the lever 370 and applying the brake. 125

The trip rod 380 is connected (Fig. 1) by 130

a split clamp operated by a screw 382 to a member 384 which is pivoted at 386 to the treadle lever 362. Depression of the treadle to engage the friction disks 356, 358 will 5 concurrently lift the rod 380 and cause its beveled end to swing the member 374 about its operating eccentric 376 and release the detent 372 from the end of the lever 370, the brake shoe being then raised by a suitable spring (not shown). The beveled end of the trip rod 380 is maintained in operative relation to the roll 378 when the screw 382 is released to permit the machine head to be raised or lowered. For this purpose 10 a sleeve 388 has a sliding fit on the rod 380 and provides a long bearing therefor to minimize wear. The upper end of the sleeve is conical and engages a hole in a portion 390 of the frame, through which the rod extends, to centralize the rod in the hole. On the lower end of the sleeve is a framewise portion 391 through the lower end of which the rod 380 passes and between which and an adjustable collar 392 is arranged a spring 393 15 to depress the rod and maintain the sleeve 388 pressed upwardly into the hole in the frame. Within the frame 391 an arm 394 is clamped to the rod and has a slot 395 in its upwardly extending end which engages a fixed pin 396 on the frame. An adjusting screw 397 engages the pin and limits depression of the arm 394 and the rod 380. This pin and slot connection also prevents rotation of the rod 380 so that the operative relation of the 20 beveled end of the rod to the roll 378 is maintained when the screw 382 is loosened. By merely loosening the screw 382 and clamp screw 398 (Fig. 1), which holds the neck of the machine head in the column, a screw 399 may be turned to adjust the head vertically, it being understood that the described splined connection between the rock-shaft 170 and lever 228, and between the sleeve 264 and the arm 260, permits movement of the rock-shaft and sleeve with the 25 head.

In work on McKay shoes conditions are somewhat different from those which obtain when operating on welt shoes. In McKay work the tacks are all completely inserted; longer tacks are required for use at the ends of the shoe instead of at the sides as in welt work, and the tacks are all driven at the same distance from the shoe edge. These 30 conditions are met by the construction shown in Figs. 8 and 9. The member 194 and the mechanism for operating it to effect the shifting of the raceways and edge gages are substantially the same as in the construction already described and the description need not be repeated.

A thin edge gage 400 is secured by a screw 402 to the frame 5 of the machine head. Threaded into the rear end of the gage 400 35 is a screw 404 having a capstan head which

engages the frame. By loosening the screw 402 and turning the screw 404 the position of the gage 400 may be accurately adjusted to position the shoe to receive tacks at the desired distance from the shoe edge. A thick gage 406 is mounted on a carrier 408 which slides on inclined ribs 409 formed on the thin gage 400 and moves from a rearward position, where it is out of the way of the shoe, to a forward position where it 40 presents the thick gage 406 with its work engaging face in the same position as that of the thin gage. To the rear end of the carrier 408 is pivoted at 410 a member 412 having a depending arm 414 connected by a link 416 to a block 418 pivoted on a pin 420 secured in one end of a lever 422 the other end of which is pivoted at 424 to the member 194. Connection between the link 416 and the block 418 is made by a pin 425 45 fixed in the block 418 and arranged for lengthwise sliding movement in separated ears 427 on the rear end of the link (Fig. 8). This construction enables swinging movement of the lever to communicate rectilinear movement to the gage carrier 408. A spring 426 is wrapped about the pivot 424 and has one end engaging the member 194 and the other engaging a pin 428 on the lever 422; the lever can thus yield rearwardly relatively to the member 194, its forward movement by the spring being limited by a stop screw 429 on the member 194. Counter-clockwise movement of the member 194 from the position shown will 50 cause the thick gage 406 to be moved forward into operative position where it is locked by a spring-pressed dog 430 (Fig. 9) which drops into a recess 432 behind the carrier 408 and over the member 412. On 55 the carrier, back of the dog 430, is a stop plate 431 which engages the dog to limit forward movement of the carrier. The yielding connection of the lever 422 to the member 194 enables the movement of the member 194 to be sufficient always to move the gage carrier into operative position forward of the dog 430 whatever may be the 60 adjusted position of the gage 400, any excess movement of the member 194 being 65 taken up by the spring 426. When the lever 422 is moved rearwardly, its pull on the link 416 first rocks the member 412 on its pivot 410 to lift the dog 430 out of its position behind the carrier 408 to release the carrier 70 and then moves it and the gage rearwardly to inoperative position.

In McKay work it is customary to have the long tacks used at the ends of the shoe in the raceway 16, and of course the thick 75 rest will be in use when long tacks are required. Hence the movement of the raceways relatively to the movement of the thick gage is the reverse of that first described. Accordingly a link 411, by which the race- 80

ways are moved, is pivoted to the member 194 at 413, as shown in Fig. 8, so that it will have received a push instead of a pull when the member 194 is turned counter-clockwise. The raceway 16 will therefore be brought into operative relation to the separator when the thick gage is in use.

It will be understood that for McKay work the driver stop wedge 64 will be disconnected from its operating mechanism or both wedges 63, 64 removed and a block of the thickness of the wedge 63 inserted to take the blow of the driver after the tack is completely inserted.

Having thus described my invention, what I claim as new and desire to secure by Letters Patent of the United States is:

1. In a lasting machine, the combination of a gripper, mechanism for imparting plaiting movements to the gripper comprising a rock-shaft, a member pivoted to said shaft, connections from said member to the gripper to impart lateral movements to the gripper, and means under the control of the operator for turning said member on its pivot to vary the movement imparted to the gripper through said connections.

2. In a lasting machine, the combination of a gripper, means for actuating the gripper to seize and pull an upper, and means to actuate the gripper to form plaits in the upper comprising a rocking member, an arm pivoted to said member on an axis passing through the axis of the rocking member, and connections from the other end of said arm to the gripper.

3. In a lasting machine, the combination of a gripper, means for actuating the gripper to seize and pull an upper, and means to actuate the gripper to form plaits in the upper comprising a rocking member, an arm pivoted at one end to said member, connections from the other end of said arm to the gripper, and a knee lever connected to said arm to vary its position about said pivot.

4. In a lasting machine, the combination of a gripper, plaiting mechanism comprising a rock-shaft, a member pivoted on an axis extending transversely of said shaft, connections from said member to the gripper, and means under the control of the operator for shifting said member on its pivot.

5. A shoemaking machine having, in combination, a gripper, means for actuating the gripper to seize and pull an upper, and means to actuate the gripper to form plaits in the upper comprising a rocking member, an arm pivoted to said member on an axis extending transversely of the member, and connections from said arm to the gripper.

6. A shoemaking machine having, in combination, a gripper, means for actuating the gripper to seize and pull an upper, and

means to actuate the gripper to form plaits in the upper comprising a rocking member, an arm pivoted to said member on an axis extending transversely of the member, connections from said arm to the gripper, and a knee lever connected to said arm to vary its position about said axis.

7. In a lasting machine, a gripper, and gripper operating mechanism comprising a rocking sleeve, an arm pivoted to the sleeve to extend axially thereof and to be swung so that its outer end will be above or below the axis of the sleeve, a rod connected to the outer end of said arm and to the gripper, and means extending through said sleeve for swinging the arm.

8. In a lasting machine, a gripper, gripper operating mechanism comprising a rocking shaft, an extension pivoted to the shaft on an axis extending transversely of the shaft, a link connecting said extension to the gripper, and means for adjusting said extension about its axis while the rock-shaft is in motion.

9. In a lasting machine, the combination of a gripper, gripper operating mechanism including a rock-shaft, a member connected to said shaft to receive rocking movement therefrom, a link connecting said member to the gripper, the point of connection of said link and member being movable above and below the axis of the rock-shaft from a neutral position in a plane including said axis, and means for adjusting said point of connection above or below said axis while the rock-shaft is in motion.

10. In a lasting machine, the combination of a gripper, means for actuating the gripper to seize and pull an upper, and means to actuate the gripper to form plaits in the upper including a rocking sleeve, a two-armed lever pivoted to said sleeve, connections from one arm of the lever to the gripper, and a rod passing through the sleeve and connected to the other arm of said lever for tipping the lever on its pivot to cause varied movement to be imparted from the lever to the gripper.

11. In a lasting machine, the combination of a gripper, means for actuating the gripper to seize and pull an upper, means to actuate the gripper to form plaits in the upper including a rocking sleeve, an arm pivoted to said sleeve, connections from said arm to the gripper, a rod passing through the sleeve and connected to said arm so that longitudinal movement of the rod will cause the arm to turn on its pivot and vary the movement of the gripper, and a rock-shaft under knee control having connection to said rod for moving the rod longitudinally in the sleeve.

12. A shoemaking machine having, in combination, a gripper, means for actuating the gripper to seize and pull an upper, and

- means to actuate the gripper to form plaits in the upper including a rocking sleeve, an arm pivoted to said sleeve on an axis extending transversely of the sleeve, connections from said arm to the gripper, and a rod passing through the sleeve and connected to said arm for tipping the arm on its axis to cause varied movement to be imparted from the arm to the gripper.
- 10 13. A shoemaking machine having, in combination, a gripper, means for actuating the gripper to seize and pull an upper, means to actuate the gripper to form plaits in the upper including a rocking sleeve, an arm pivoted to said sleeve on an axis extending transversely of the sleeve, connections from said arm to the gripper, a rod passing through the sleeve and connected to said arm for tipping the arm on its axis to cause varied movement to be imparted from the arm to the gripper, and a rock-shaft under knee control having connection to said rod for moving the rod longitudinally of the sleeve.
- 15 14. In a lasting machine, a gripper arranged for updraw movements, a yoke for imparting overdraw movements thereto, a carrier connected to the gripper and arranged for lateral movements in said yoke, a lever yieldingly mounted on said yoke, a connecting rod directly connected to said lever, and means for moving the connecting rod to impart yielding lateral movements to the gripper.
- 20 15. In a lasting machine, the combination of a rocker having connection to the machine to cause it to be rocked during operation of the machine, a link connecting the rocker to the gripper for imparting lateral movements to the gripper, a slide on said link, a lever pivoted to the slide, and connections between the other end of said lever and the gripper for imparting twisting movements thereto.
- 25 16. In a lasting machine, a gripper arrangement for updraw movements, a yoke for imparting overdraw movements thereto, a carrier connected to the gripper and arranged for lateral movements in said yoke, a T-lever pivoted to the carrier, a bar across the top of the T-lever, yielding means to press the bar toward the lever, screw means between the bar and the T-lever for varying their relation to each other, an inextensible rod connected to the stem of the T-lever, and means for operating the rod to move the gripper laterally.
- 30 17. In a lasting machine, the combination of a gripper, a gripper carrier, a T-lever on the gripper carrier through which yielding movements are imparted to the gripper, a rocking member, and a link connected directly between the rocking member and the T-lever.
- 35 18. In a lasting machine, a gripper having a shank suspended for universal movement, a carrier embracing said shank, a T-lever pivoted to the carrier, a spring-pressed bar resting on the cross-bar of the T-lever, means for adjusting points of contact of the bar with the T-lever, and a link having a ball joint connection to the stem of the T-lever and actuated to impart lateral movements to the gripper.
- 40 19. In a lasting machine, the combination of a gripper having a ball-ended shank suspended for universal movement, a carrier embracing said shank, a T-lever pivoted to the carrier, a link having a ball joint connection to the stem of the T-lever and actuated to impart lateral movements to the gripper, a slide on said link carrying a pin, a lever through one end of which said pin extends, and connections from the other end of the lever to the ball-ended gripper shank for effecting twisting movements of said shank.
- 45 20. In a lasting machine a gripper arranged for updraw movements, a yoke for imparting overdraw movements thereto, a carrier connected to the gripper and arranged for lateral movement in said yoke, a lever yieldingly mounted on said carrier, a connecting rod having a ball joint connection to said lever, means for moving the connecting rod to impart yielding lateral movements to the gripper, a slide movable transversely of said rod, and connections from said slide to the gripper for imparting twisting movements thereto.
- 50 21. In a lasting machine, a power shaft, a cam on the shaft, a wiper slide carrying a wiper and movable toward and from the shoe, and a roll carried by said slide and engaging said cam.
- 55 22. In a lasting machine, a power shaft, a cam on the shaft, a wiper slide carrying a wiper and movable toward and from the shoe, a bracket secured to the slide, and a roll on the bracket having its axis extending radially of said cam, said cam having a path in its edge face engaged by said roll and contoured to reciprocate the slide.
- 60 23. In a lasting machine, a power shaft, a cam on the shaft, a wiper slide carrying a wiper and movable toward and from the shoe, a bracket secured to the slide by screw and slot connections, screw means between the slide and bracket for adjusting the slide and bracket relatively, and cam means acting on the bracket to reciprocate the slide.
- 65 24. In a lasting machine, a reciprocating wiper slide, a peripheral path cam for operating the slide, a tapered roll on the slide engaging said cam, and an adjustable bearing plate engaging the slide to oppose the tendency of the roll to leave the cam path.
- 70 25. In a lasting machine, a gripper, an updraw lever for imparting updraw movements to the gripper, a rock-shaft mounted on said updraw lever, an arm on the rock-

- shaft for closing the gripper, a second arm on the rock-shaft carrying a roll, a cam acting on said roll to close the gripper, and flange and groove connections between the 5 roll and cam to maintain the roll in constant operative relation to the cam as the updraw lever is tipped.
26. In a lasting machine, a gripper, an updraw lever for imparting updraw movements to the gripper, a rock-shaft mounted on said updraw lever, an arm on the rock-shaft for closing the gripper, a second arm on the rock-shaft having an elongated pin, a roll arranged to slide on the pin, an edge 10 cam acting on said roll to close the gripper, and means for maintaining said roll and cam against relative edgewise movement as the updraw lever is operated.
27. In a lasting machine, gripper actuating mechanism comprising a rock-shaft having a tipping movement transversely of its axis, an operating cam for said rock-shaft which does not partake of said tipping movement, an arm on said rock-shaft having 15 a pin, a roll on the pin through which the pin is movable as the rock-shaft is tipped, and means for preventing relative movement of the engaging faces of the cam and roll in the direction of their line of contact.
28. In a machine of the class described, the combination of a gripper actuating mechanism comprising a rock-shaft having a tipping movement transversely of its axis, an operating cam for the rock-shaft which does 20 not partake of said tipping movement, an arm on the rock-shaft adjacent to the cam, a pin on said arm, and a roll on the pin arranged to engage the cam, the arrangement being such that the pin may move endwise on the roll during tipping of the rock-shaft while the roll remains at rest with respect to movement transversely of the cam.
29. In a machine of the class described, the combination of a lever of the first class, 25 a rock-shaft journaled on the lever and having a roll carrying operating arm adjacent to the fulcrum of the lever, an operating cam for the arm having a fixed axis and engaging the roll, and means between the roll and the arm to permit rotation of the roll and relative movement between the roll and the arm in the direction of the axis of the roll.
30. In a lasting machine, gripper actuating mechanism comprising a cam shaft, an updraw lever mounted above the cam shaft and tipping about an axis transverse to said shaft, a gripper closing rock-shaft mounted in bearings on the gripper lever and having 30 an operating arm, a cam on the cam shaft to actuate the arm of the rock-shaft, a roll mounted on the arm and engaging said cam, and means permitting relative movement between the roll and the arm in the direction of the line of contact between the roll and the cam.
31. In a lasting machine, gripper actuating mechanism comprising a cam shaft, an updraw lever mounted above the cam shaft and tipping about an axis transverse to said shaft, a gripper closing rock-shaft mounted 35 in bearings on the gripper lever and having an operating arm, a cam on the cam shaft to actuate the arm of the rock-shaft, a pin on said arm, and a roll on the pin of less width than the length of the pin so that the roll may remain squarely in engagement with the cam as the rocking lever is tipped with the updraw lever and the pin may move endwise transversely of the plane of rotation of the roll.
32. In a lasting machine, gripper actuating mechanism comprising a cam shaft, an updraw lever mounted above the cam shaft and tipping about an axis transverse to said 40 shaft, a gripper closing rock-shaft mounted in bearings on the gripper lever and having an operating arm, a cam on the cam shaft to actuate the arm of the rock-shaft, a pin on said arm, a roll on the pin of less width than the length of the pin, a groove in the cam, and a rib on the roll engaging said groove to prevent relative movement of the cam and the roll in the direction of their line of contact.
33. In a machine of the class described, edge gage shifting mechanism comprising a power reciprocated member, a bracket adjustably mounted on the member, a spring-pressed pawl mounted on the bracket, means for adjusting the bracket on the reciprocated 45 member to vary the effective throw of the pawl, and a ratchet acted upon by said pawl.
34. In a machine of the class described, edge gage shifting mechanism comprising a power reciprocated member, a bracket adjustably mounted on the member, a spring-pressed pawl mounted on the bracket, means for limiting the movement of the pawl due to the spring, means for adjusting the bracket on the reciprocated member to vary the effective throw of the pawl, and a ratchet 50 acted upon by said pawl.
35. In a machine of the class described, an edge gage arranged for movement into and out of operative position, a sliding member, connections between the gage and the sliding member, means including a pawl, a ratchet and a cam for moving the sliding member, and a pawl having two teeth one 55 to prevent backward movement of the ratchet when in one position and the other to prevent backward movement of the ratchet when in another position.
36. In a machine of the class described, an edge gage, edge gage shifting mechanism comprising a sliding member, a ratchet and a cam on the ratchet engaging the sliding member, a power operated pawl to operate the ratchet, and a second pawl having a fixed 60

pivot acting to prevent reverse movement of the ratchet.

37. In a machine of the class described, an edge gage and edge gage shifting mechanism comprising a sliding member, a ratchet and a cam on the ratchet operating to move the sliding member to and fro, a power operated pawl to operate the ratchet, and a second pawl having two teeth which operate alternately to prevent reverse movement of the ratchet in different positions of the ratchet.

38. In a lasting machine, the combination of an edge gage, means for shifting the edge gage to and fro into and out of operative position comprising a rotary cam for imparting to and fro movements to the gage, a ratchet cooperating with the cam, a power operated, normally inoperative pawl for operating the ratchet, and manual means for giving the ratchet an initial movement to cause it to be picked up by the pawl, said cam being formed with concentric surfaces to prevent movement of the gage during the manual movement of the cam by the pawl.

39. In a lasting machine, an edge gage, a member connected to the gage to move the gage into and out of operative position, a cam for operating said member, a ratchet connected to said cam and having flat faces between its teeth, a constantly reciprocating pawl opposite to one of said flat faces and having an extension beyond its pivot, a spring plunger arranged opposite said extension as the extension slides to and fro, and manual means for initiating movement of the ratchet to cause the pawl to pick up the ratchet and move the cam to shift the gage, said plunger acting by increased leverage to prevent the pawl from moving the ratchet too far.

40. In a lasting machine, lasting instrumentalities adjustable for operation on different parts of the shoe, normally inoperative power means comprising a ratchet and a continually moving pawl for shifting said instrumentalities from a position of adjustment for use on one part of the shoe to a position of adjustment for operation on another part of the shoe, manually operated means for imparting an initial movement to said ratchet to cause it to be picked up by the moving pawl to cause shifting of said instrumentalities, and a pawl for holding said ratchet in either its normal position or in the position to which it is manually shifted.

41. In a lasting machine, a reciprocating wiper slide, a pawl mounted on the slide having an extension beyond its pivot, a normally inactive spring plunger opposite said extension and acting against the extension if the pawl is moved on its pivot, and a ratchet having flat faces between its teeth one of which faces lies opposite to and par-

allel with the pawl, there being normally no frictional engagement between the plunger and extension nor between the pawl and the ratchet.

42. In a lasting machine, a reciprocating wiper slide, a pawl carried by the slide and having parallel faces extending in the direction of its reciprocation, a ratchet having flat faces between its teeth one of which is normally parallel to one of the faces on the pawl, a spring plunger having limited movement toward the other face of the pawl, the pawl being normally reciprocable past the ratchet and the plunger without frictional contact with either, the plunger being brought into action when the ratchet is turned to cause a tooth to engage the pawl.

43. In a machine of the class described, the combination of a pair of edge gages each arranged for use to the exclusion of the other and each arranged for sliding movement into and out of operative position, power means for shifting the gages, and means under control of the operator for causing the power shifting to be effected.

44. In a machine of the class described, the combination of a pair of edge gages each arranged for use to the exclusion of the other and each arranged for sliding movement into and out of operative position in converging paths, power means for shifting the gages, and means under control of the operator for causing the power shifting to be effected.

45. In a machine of the class described, the combination of a fastening inserting mechanism, a thin edge gage arranged for horizontal movement into and out of operative position, a thick edge gage arranged for movement into and out of operative position in a path inclined to the horizontal to cause the thick gage when in its operative position to assume the same position vertically as the thin gage when in its operative position, and power means under control of the operator to cause either gage to be presented in operative position.

46. In a machine of the class described, the combination of a fastening inserting mechanism, a thin edge gage arranged for horizontal movement into and out of operative position and adapted when in its outer position to locate a shoe for the reception of fastenings at one distance from the last edge, a thick edge gage arranged for movement into and out of operative position in a path inclined to the horizontal and adapted when in its operative position to locate the shoe for the reception of fastenings at a different distance from the last edge, and power means under control of the operator to cause either gage to be presented in operative position.

47. In a lasting machine, a thin edge gage, a thick edge gage movable relatively to the

thin gage into and out of operative position, power operated means for moving the thick gage into operative position, and means for locking the gage in said position.

5 48. In a lasting machine, a thin edge gage, a thick edge gage movable relatively to the thin gage into and out of operative position, power operated means for moving the thick gage into operative position, means for locking the thick gage in said position, and means operated by reverse movement of the power operated means for unlocking the gage and returning it to normal position.

10 49. In a lasting machine, a thin edge gage and a thick edge gage arranged for alternative use, a carrier for the thick gage, power operated means for moving the thick gage carrier to move the thick gage into and out of operative position comprising a yielding lever, a locking dog engaging the carrier when moved by the lever into operative position and holding the carrier against movement in either direction, and means engaging said dog when the lever is moved in the opposite direction to release the dog and permit movement of the carrier.

15 50. In a lasting machine, an edge gage carrier, power means for moving the carrier yieldingly in one direction and positively in the other direction, a stop to limit said movement of the carrier in the direction in which it is moved yieldingly, a positive lock for preventing movement of the carrier in the direction in which it is moved positively, and releasing means for disengaging the lock operated by the initial movement of the power means in the direction of positive movement.

20 51. In a machine of the class described, a column, a head vertically adjustable on the column, lasting instrumentalities carried by the head, a vertical rock-shaft, connections therefrom to some of said instrumentalities for controlling them, a slotted sleeve-shaft surrounding said rock-shaft, connections between said sleeve-shaft and other lasting instrumentalities for controlling them, a knee lever pivotally fixed to the

column and splined to the rock-shaft, and a lever pivoted on the shaft and engaging the slot in the sleeve, said lever being connected to the knee lever and the head being adjustable without disturbing the connections between the rock-shaft, the sleeve shaft and the knee lever.

25 52. In a lasting machine, a column, a head vertically adjustable on the column, power operated lasting instrumentalities on the head, a rock-shaft extending from the head to a point on the column and having connections for controlling said instrumentalities, and a lever for operating the rock-shaft so connected to the rock-shaft that said shaft may be adjusted vertically with said head while the lever remains operatively connected to the shaft.

30 53. In a lasting machine, a column, a head vertically adjustable on the column, power operated lasting instrumentalities on the head, controlling mechanism for said instrumentalities including vertical rock-shafts, and a control lever mounted on the column and operatively connected to the rock-shafts so that either may be operated independently of the other, said operative connections being constructed and arranged to permit the head to be vertically adjusted without disturbing said operative connections.

35 54. In a lasting machine, a column, a head vertically adjustable on the column, power operated lasting instrumentalities on the head, controlling mechanism for said instrumentalities including concentric rocking members, and a control lever mounted in fixed vertical relation on the column and operatively connected to each of said members to rock them independently, said operative connections being arranged to permit vertical movement of the members with the head without disturbing their operative connections to the lever.

40 In testimony whereof I have signed my name to this specification.

THOMAS H. SEELY.
